UNITED STATES PATENT OFFICE.

JACOB S. JAMMER, OF NEW YORK, N. Y., ASSIGNOR TO WESTERN ELECTRIC COMPANY,
INCORPORATED, OF NEW YORK, N. Y., A CORPORATION OF NEW YORK.

CARRIER SIGNALING SYSTEM.

Application filed September 20, 1923. Serial No. 663,745.

To all whom it may concern:

Be it known that I, JACOB S. JAMMER, a citizen of the United States of America, residing at New York city, in the county of New York and State of New York, have invented certain new and useful Improvements in Carrier Signaling Systems, of which the following is a full, clear, concise, and exact description.

10 This invention relates to a carrier signaling system.

Multiplex carrier telephone and carrier telegraph systems as heretofore employed extend between terminal stations from which 15 radiate low frequency lines which are either permanently connected, one to each of the carrier channels with a multiplex system or any of which may be temporarily connected to any one of the carrier channels by the operators at the respective terminal stations.

In some multiplex systems where the low frequency lines are permanently coupled to the carrier channels of the multiplex system, the low frequency lines extend to other 20 stations which are geographically separated.

For example, a multiplex carrier telephone system between Chicago, Illinois, and Harrisburg, Pennsylvania, has permanently coupled to the channels thereof low frequency lines extending from Harrisburg to 25 New York and Washington. Frequently, when all of the usual channels to either point are busy, it is desired to obtain another channel to one or the other of said points.

In accordance with the present practice this is accomplished by calling, say, the New York operator who connects to the Chicago-New York channel, a low frequency line extending from New York to Washington. This practice is not only cumbersome but time consuming and utilizes lines which should be available for other service. It is, therefore, desirable that in 30 case, for example, the usual Chicago-Washington channels are busy, the Chicago operator be able to establish another channel between Chicago and Washington without the necessity of going through the station at New York. This represents, of course, but one of many situations in which it 35 would be desirable to control the establishment of a connection from a distance, over a desired carrier channel.

One of the objects of this invention, therefore, is to provide a multiplex carrier signaling system wherein any one of a plurality of low frequency lines radiating from one multiplex terminal station may be selected and coupled to a channel of the multiplex system under control of the other multiplex terminal station. 55 60

Other objects and features of the invention relate to the arrangements for selecting the desired radiating low frequency line 65 and the proper balancing network therefor, to the signaling and busy test arrangements associated with the system.

While the invention is being disclosed as applied to a multiplex carrier telephone system, it will be understood that it may be applied to a multiplex carrier telegraph or other signaling system. 70

In the drawings—

Figs. 1 and 2 when placed end to end in 75 the order named, show a multiplex carrier telephone system and low frequency lines radiating from one of the terminal stations, either of two of which may be selected and coupled to a channel of the system. 80

Figs. 3, 4 and 5 when placed end to end in 85 the order named, show a multiplex carrier telephone system similar to that of Figs. 1 and 2 but wherein a call may be initiated from either end.

The multiplex carrier telephone system of Figs. 1 and 2 comprises, in general, a high frequency main line ML extending between terminal stations X and Y. The apparatus located at station X is shown to the right of the dotted line in Fig. 1 while the apparatus located at station Y is shown to the left and below the dotted line in Fig. 2. The main line ML terminates at station X in a plurality of transmitting and receiving branches TC₁, TC₂ and TC₃, and RC₁, RC₂ and RC₃, and at station Y in similar transmitting and receiving branches. 90 95

Different carrier frequencies are employed 100 for the different channels of the system.

The frequencies employed for transmission in one direction are comprised within an entirely different range from those employed for transmission in the opposite direction. 105

The transmitting branches are similar so a description of one will suffice.

Transmitting branch TC₁ includes a

modulator M_1 , to which carrier current of the frequency assigned to the channel is supplied from the source O_1 , and a band filter TBF_1 .

5 The modulator M_1 may be of any well known type, such, for example, as the electronic valve modulator disclosed in Fig. 42 of the article entitled "Carrier current telephony and telegraphy" by Colpitts and 10 Blackwell, published in the transactions of American Institute of Electrical Engineers, volume 40, 1921.

15 The filter TBF_1 is of the type disclosed in the U. S. patent to Campbell, 1,227,113, May 22, 1917. It is designed to pass currents of the carrier frequency and of the frequencies within either the upper or lower side band thereof and to suppress currents of all other frequencies.

20 The receiving branches are similar so that a description of one will suffice.

The receiving branch RC_1 includes a band filter RBF_1 , an amplifier A_1 , a demodulator DM_1 and a low pass filter LPF_1 .

25 The band filter RBF_1 is of the type disclosed in the Campbell patent supra and is designed to pass currents of the carrier frequency assigned to this channel and of the frequencies within the same side band 30 as is transmitted by filter TBF_1 , and to suppress currents of all other frequencies.

The amplifier A_1 and the demodulator DM_1 may be of any well known type, such, for example, as those disclosed in Fig. 42 35 of the Colpitts and Blackwell article, supra.

The low pass filter LPF_1 is of the type disclosed in the Campbell patent and is designed to pass currents of frequencies below 40 the upper limit of the voice range of frequencies and to suppress currents of higher frequencies.

45 Each pair of transmitting and receiving branches are similarly connected to a low frequency circuit. For example, the associated transmitting and receiving branches TC_1 and RC_1 are coupled to and conjugately related with respect to a low frequency circuit C_1 by means of a three-winding transformer 1 and a balancing artificial line or network N_1 .

50 The low frequency circuits C_2 and C_3 coupled to transmitting and receiving branches of the multiplex system at the station X , may extend to and terminate in jacks at a switchboard in the usual manner. This switchboard may be located at the station X , or, at a distant station.

55 Likewise, each of the associated receiving and transmitting branches at station Y may be similarly connected to low frequency circuits. The low frequency circuits C_2^2 and C_3^2 are low frequency lines permanently connected to channels No. 2 and No. 3 respectively. Line C_2^2 extends to one dis-

tant station and line C_3^2 to another distant station, which, for purposes of convenience, have been designated New York and Washington.

Low frequency lines L_1 and L_2 radiating 70 from station Y extend to the same distant stations as low frequency lines C_2^2 and C_3^2 . For purpose of illustration lines L_1 and L_2 are assumed to have approximately 75 the same electrical characteristics so that either may be balanced by the same balancing network. However, if these lines have substantially different electrical characteristics compensation therefor may be effected 80 in any desired manner, such for example as by employing different balancing networks as will be described in connection with the system of Figs. 3, 4 and 5.

The low frequency circuit C_1 terminates 85 in open contacts of two relays 2 and 3 so that, upon the operation of either relay, the low frequency circuit C_1 may be extended to the terminals of jack J_1 or J_2 depending upon which relay is operated.

Normally, carrier current of the frequency assigned to channel No. 1 and of the upper magnitude, as explained below, is flowing therethrough from station X to station Y . This current is rectified by the rectifier R_1 associated with receiving branch R_1C_1 . The resulting rectified current flows through relay 4, causing it to hold its armature in mid-position between the two contacts associated therewith. The magnitude of this current is controlled by 95 a resistance 5 normally bridged across the output of modulator M_1 through the contact of relay 6 which is normally energized.

100 Relay 4 controls selecting and coupling means comprising relays which select the desired low frequency line and connect the same to the low frequency circuits C_1 . The low frequency lines subject to selection are lines L_1 and L_2 , the former extending 105 to New York, for example, and the latter to Washington. Each of these lines terminates in a jack J (only one of which is shown) which has associated therewith signal receiving means.

110 The operator at the station where the jacks in Fig. 1 terminate, desiring to establish a connection to Washington by way of the high frequency channel with which either of the low frequency lines L_1 and L_2 115 may be associated, inserts the plug P of cord circuit CC into jack J_2 . Relay 3 thereupon operates connecting the low frequency circuit C_1 to the tip and ring terminals of the jack and operating busy signals BS associated with the jacks. The actuation of 120 ringing key RK impresses a source of low frequency signaling current onto relay 16' and causes the operation thereof. The 125 operation of relay 16' causes the release of relay 6 which removes resistance 5 from 130

bridged relation to the output of modulator M_1 . As a result of this action the magnitude of the carrier current transmitted through the channel is increased and the 5 amount of rectified current through relay 4 increases. Relay 4 thereupon closes its left-hand contact causing the operation of relays 7 and 8. Relay 8 locks up through a contact thereof and the closed contact of relay 9. The operation of relay 8 selects the low frequency line L_1 and connects the same to the low frequency circuit C_1 . A busy tone from source BT normally connected to the low frequency lines is disconnected 10 from line L_1 by the operation of relay 8.

The operation of relay 7 causes the energization of relay 10 which connects a source of signaling current 11 to the selected low frequency line L_1 causing the operation of 20 relay 12 associated with jack J. The operation of relay 12 lights signal lamp 13 and energizes relay 14 which locks up through its contact and the contact of relay 15.

Upon the restoration of the ringing key 25 RK to its normal position, relay 16 releases and relay 6 operates, again bridging resistance 5 across the output of modulator M_1 . In response thereto, relay 4 allows its armature to return to the mid-position between 30 the contacts associated therewith whereupon relays 7 and 10 release. Ringing current 11 is, therefore, disconnected from the line L_1 which is then connected through the contacts of relays 8 and 10 to the line windings 35 of the three-winding transformer which in turn couples the low frequency line L_1 to the associated transmitting and receiving branches T_1 , C_1 and R_1 , C_1 of the multiplex system.

40 The operator at the distant end of the low frequency line L_1 upon observing the lighted condition of the signal lamp 13 may insert the plug of a cord circuit, similar to that shown in Fig. 1, into the jack J to answer the call. Relay 15 thereupon operates, opening the locking circuit of relay 14 which releases, extinguishing the lamp 13. The operator at the distant station associated with 45 low frequency line L_1 may then communicate with the operator at the other station and receive instructions for completing the desired connection, after the establishment of which, conversation may take place in the ordinary manner usual to multiplex carrier telephone systems.

50 At the conclusion of the conversation, the operators withdraw the plugs from the jacks, whereupon relays 3 and 15 return to their normal condition. Relay 8, however, remains locked up so that the low frequency line L_1 remains coupled to the transmitting and receiving branches T_1 , C_1 and R_1 , C_1 of the channel of the multiplex system.

55 Should the operator now desire to establish connection over the low frequency line

L_2 , the plug P is inserted in the jack J_1 . Relay 2 thereupon operates, connecting the low frequency circuit C_1 through to the tip and ring terminals of the jack J_1 and operating the busy signals BS. The actuation of 60 ringing key RK operates relay 16 which releases relay 17. Relay 17 thereupon closes its contact which places a short-circuit across the output of the modulator M_1 and reduces to nil, the magnitude of carrier current 65 transmitted through the channel. The magnitude of the rectified current through relay 4 is, therefore, reduced thereby allowing the armature of the relay to close its right-hand contact. Relays 18 and 9 then operate. Relay 18 locks up through one of its contacts 70 and the closed contact of relay 7. The operation of relay 9 opens the locking circuit of relay 8 which thereupon disconnects low frequency line L_1 from circuit C_1 . Relay 18, 75 in operating, connects low frequency line L_2 to the low frequency circuit C_1 . Relay 9 in closing its front contact, energizes relay 10 which connects ringing current from the 80 source 11 to the low frequency line L_2 and operates the ringing response relay associated with the jack at the distant end thereof, whereupon the signal lamp thereat is lighted. The restoration of the ringing key 85 to normal position releases relay 16, energizes relays 17 and 4 and deenergizes relays 9 and 10.

The multiplex carrier telephone system of 90 Figs. 3, 4 and 5 is similar to that of Figs. 1 and 2 in that it comprises a high frequency main line ML terminating at two geographically separated terminal stations W and E in a plurality of transmitting and receiving 95 branches which are associated in pairs, each pair of which may be coupled to a low frequency circuit or line.

100 At each terminal, the transmitting and receiving branches are coupled to the main line ML through a three-winding transformer T , one winding of which is in series with the main line. The second winding is connected to the band filters of the transmitting branches and the third winding is connected to the receiving branches.

105 This system, as illustrated, has three channels. Two of these channels No. 2 and No. 3, are coupled in the usual manner through three-winding transformers to low frequency lines LFL_2 and LFL_3 extending from the terminal station W and lines LFL_2 and LFL_3 extending from station E .

110 Different carrier frequencies are employed for the different channels of the system. The frequencies employed for transmission in one direction are comprised within an entirely different range from those employed for transmission in the opposite direction.

115 Each end of channels No. 2 and No. 3 is equipped with means whereby signals incoming over the low frequency line may be 120

translated into signals outgoing over the high frequency line and for translating the signals incoming over the high frequency line into signals outgoing over the low frequency line. Since this equipment for each end of the two channels is alike, it is shown in detail in connection with only one channel and at one end thereof only.

This signaling transmitting equipment 10 may be described in connection with the operation. Thus, low frequency signaling current incoming to the multiplex terminal station over low frequency line LFL_2 operates relay 25, thereby causing the release of relays 26 and 27. The resultant closure of the contact of relay 27 short-circuits the output circuit of the modulator M_2 thereby preventing the flow of carrier current of the frequency assigned to this channel over the 15 main line. When a ringing signal is incoming over the main line, as indicated by the absence of carrier current therefrom, relay 28 in the output circuit of rectifier R_2 releases causing the energization of relay 29 which thereupon closes its contacts. The closure of the right-hand contact short-circuits the midpoints of the line windings of the hybrid coil thereby preventing singing during the ringing operation. The closure of the 20 left-hand contact operates relay 30 which connects a source of ringing current 31 to the low frequency line LFL_2 .

Channel No. 1 of the multiplex carrier 25 telephone system illustrated in Figs. 3, 4 and 5 has associated therewith apparatus and circuits so organized that any one of five low frequency circuits, four outgoing and one incoming, may be coupled to the carrier channel at the terminal station W. At the terminal station E there is provided apparatus 30 controlled from terminal station W for selecting any one of four outgoing low frequency lines, applying low frequency ringing signal current to the selected low frequency line, applying a busy tone to a non-selected low frequency line, selecting and connecting the proper balancing network to the selected low frequency line and finally connecting the selected low frequency line and its balancing network to channel No. 1. The selection is effected by shifting the frequency of the carrier current transmitted over the main line ML and selectively operating at the distant terminal receiving relays associated with rectifiers coupled to the channel 35 through selective circuits.

The operator at terminal station W, desiring to establish connection by way of channel No. 1 over the low frequency line AL extending from station E to a distant station, may insert the plug of a cord circuit, similar to that shown in Fig. 1, into jack A thereby causing the operation of relay 32. Relay 32 operates busy signals BS associated with each of the jacks A to E inclusive

and also operates relay 33. Relay 33 connects the tip and ring terminals of jack A to the line windings of the three-winding transformer 1. Relay 33 also causes the operation of relay 34 over a circuit including ground connection 34' which thereupon closes the filament circuit of the electronic valve of oscillator SO which renders the oscillator active in the generation of oscillations of the frequency assigned to channel 75 No. 1 for transmission over the main line from station W to station E. Carrier current of the frequency generated by oscillator SO and transmitted over the main line ML is selected by the tuned circuit TC and impressed upon the rectifier R. The resultant rectified current flowing in the output circuit of the rectifier energizes relay 35 whereupon relay 36 releases and relay 37 operates. Relay 37, in operating, closes the 80 filament circuits of rectifiers AR, BR, CR and DR.

After the insertion of the plug in the jack A, the ringing key of the associated cord circuit is actuated causing the operation of relay 38. The operation of relay 38 causes the energization of relay 39 which connects condenser 40^a in parallel with the condenser of the frequency determining circuit associated with the oscillator, thus changing the frequency of the current generated thereby. The oscillator now generates and transmits over the main line, current of a different frequency which is selected by the tuned circuit ATC and impressed upon the rectifier 90 AR. The resultant rectified current in the output circuit of the rectifier AR causes the operation of relay 41. Relays 42 and 43 thereupon operate. Relay 42 selects low frequency line AL and causes the operation 100 of relay 61 which short circuits a winding of transformer 44 to prevent singing during the ringing operation. At the time of the change in frequency of the current generated by the oscillator, relay 35 releases and relay 36 operates. Relay 37 being a slow release relay holds up until relay 43 operates and supplies a ground for completing the locking circuit of relay 37. Relay 43, in operating, 105 locks up over a circuit including one of its contacts and the contact of relay 36. The operation of relay 43 also causes the operation of relay AN which connects in series with the line windings of the three-winding transformer 44, a balancing network NA to balance the selected low frequency line AL. 110

The operation of relay 43 also causes the operation of relays 45, 58, 62 and 63. Relay 45 connects a source of ringing current 46 to the selected low frequency line AL. Relays 58, 62 and 63 connect a busy tone from source BT to the non-selected low frequency lines BL, CL and DL. The distant end of the low frequency line AL is terminated in a jack similar to jack J shown in 115 120 125 130

Fig. 2 and has associated therewith similar signal receiving apparatus so that in response to the connection of ringing current from source 46 to the selected low frequency line AL, the signal lamp at the distant end thereof is lighted.

- Upon restoration of the ringing key to normal position, relay 38 releases thereby releasing relay 39 which shifts the frequency 5 of the current generated by the oscillator back to normal. Relay 41 thereupon releases and relay 35 operates. Upon the 10 operation of relay 35, relay 36 releases but relay 36 is slow to release so that a ground 15 is substituted at a front contact of relay 45 before being removed at the contact of relay 36, whereby relays 43, AN, 45, 58, 62 and 63 remain locked up. Relay 42, however, controlled through a contact of relay 41 releases 20 thereby disconnecting ringing current from the low frequency line AL and connecting this line through to the three-winding transformer 44. Relay 61 releases when relay 42 releases.
- 25 The operator at the distant end of the selected and connected low frequency line AL observing the lighted condition of the lamp associated therewith, may connect to the jack the plug of a cord circuit similar 30 to that shown in Fig. 1 and communicate with the operator at the initiating terminal to receive instructions as to the number of the line to which connection is desired. Since the oscillator SO' and the modulator 35 M₁ are active normally, they are in readiness to transmit the return speech from station E to station W as soon as the operator at the distant station on line AL begins to talk.
- 40 After the completion of the connection between the calling and called parties conversation may ensue at the conclusion of which the operator at station W and at the distant end of the low frequency line AL 45 may withdraw the plugs from the jacks to restore the apparatus of the system to normal condition. When the plug at station W is withdrawn from jack A, relays 32 and 34 release, thereby disabling the oscillator 50 SO. Since no current is now being transmitted by the oscillator SO, relay 35 releases and relay 36 operates. Between the time of the opening of a contact of relay 35 and the closure of the contact of relay 36, relay 43 55 releases whereupon relay 37 releases opening the filament circuit of the rectifiers AR, BR, CR and DR. The release of relay 43 also causes the release of relays AN, 45, 58, 62 and 63. Since relay 37 is held up until the 60 operator at station W withdraws the plug of her cord circuit in taking down the connection, the rectifiers AR, BR, etc. are held in readiness to respond in case of a recall by the operator at station W. This can be 65 done by merely actuating the ringing key

in the operator's cord circuit at station W, without having first to withdraw the plug.

The oscillator SO furnishes current of the normal frequency when none of the condensers 40^a, 40^b, 40^c or 40^d is connected in parallel with the condenser of the frequency determining circuit. This normal frequency is the carrier frequency assigned to channel No. 1 for transmission from west to east. An oscillator SO' at the station E furnishes 70 carrier current of the frequency assigned to channel No. 1 for transmission from east to west. This oscillator, SO', as stated, is normally operative so that current of the frequency supplied thereby is normally 80 flowing over the main line ML and this current is selected by the receiving band filter RBF₁, passes through the demodulator DM₁, the amplifier A₁ and the high pass filter HPF₁ and is delivered into the input circuit of rectifier R₁. Relay 47 is, therefore, energized by rectified current in the output circuit of the rectifier and remains energized so long as carrier current is being transmitted over the main line from the 90 oscillator SO'.

Should a call originate at the distant end of the low frequency line AL, the plug of the cord circuit thereat is inserted into the jack and the ringing key associated with the cord circuit is actuated. Relay 48 responds to the ringing current and in responding causes the operation of relays 43, AN, 45 and 49. Relay 43 locks up over a circuit including the contact of energized relay 36 100 and also maintains relays AN and 45 in locked up condition. The operation of relay 43 causes the operation of relays 58, 62 and 63 which connect a busy tone into low frequency lines BL, CL and DL. The operation of relay 49 short-circuits the output of modulator M₁ thereby stopping the transmission of carrier current from oscillator SO' to the main line. Relay 47 in the output circuit of rectifier R₁ therefore releases 105 and causes the operation of relay 50 and the lighting of signal lamp 51. Relay 50 locks up through the closed contact of relay 52 and maintains the lamp in a lighted condition. 110

Upon the restoration of the ringing key to normal position, relay 48 releases thereby causing the release of relay 49 which, in turn, allows relay 47 to operate.

The operator at station W observing the 115 lighted condition of lamp 51 inserts into the answering jack E, the plug of the cord circuit similar to that shown in Fig. 1 whereupon relay 52 operates opening the locking circuit of relay 50 and extinguishing lamp 51. The busy signals BS associated with the calling jacks A, B, C and D and the answering jack E, are operated upon the energization of relay 52. The operation of relay 52 120 also causes the operation of relay 34 which 125 130

closes the filament circuit of the electronic valve of oscillator SO. The oscillator thereupon generates current of the frequency assigned to channel No. 1 for transmission from west to east. The operators may now converse and instructions given to the operator at station W for completing the desired connection. Current of the frequency generated by oscillator SO and transmitted over the main line is selected by the tuned circuit TC and rectified by rectifier R. Relay 35 responds to the resultant rectified current. Relay 35 functions as before to operate relay 37 and to furnish a ground for the locking circuit of relay 43, which ground is substituted for that furnished through the contact of relay 36. Relay 36 releases upon the operation of relay 35 but being slow to release, this contact does not open until after the closure of the contacts of relay 35. Thus the locking circuit of relay 43 is maintained.

At the conclusion of the conversation, the plugs are withdrawn from the jacks and the apparatus is restored to normal condition in the manner previously described.

Should the operator at station W desire to establish a connection by way of channel No. 1 to the low frequency line BL, the plug of the cord circuit is inserted in the jack B whereupon relay 53 operates, causing the operation of the busy signals BS and relay 54. Relay 54 connects the tip and ring terminals of jack B to the line windings of transformer 1 and causes the operation of relay 34 which starts the oscillator SO. The oscillator SO generates and transmits over the line carrier current which is selected by the high pass filter HPF₁ and the tuned circuit TC. Relays 35 and 37 operate and relay 36 releases as before.

The operator actuates the ringing key of the cord circuit whereupon relay 55 responds, causing the operation of relay 56 which connects condenser 40^b in parallel with the condenser of the oscillator frequency determining circuit. The frequency of the current generated by the oscillator is thereby shifted and tuned circuit BTC selects this shifted frequency current and rectifier BR rectifies the same. The resultant rectified current operates relay 57 which causes the operation of relays 58 and 59. Relay 58 selects low frequency line BL, and causes the operation of relay 61. Relay 59 locks up over a circuit including the contact of relay 36 which is now operated. Relay 59 causes the operation of relays 60, BN, 42, 62 and 63. All of these relays are now locked up, due to the fact that relay 59 is locked up. Relay 60 connects ringing current to the selected low frequency line BL which lights the signal lamp at the other end. Relay BN connects balancing network NB in series with the line windings of transformer 44 to balance the selected low frequency line BL. Re-

lays 42, 62 and 63 connect a source of busy tone BT to the non-selected low frequency lines AL, CL and DL.

Upon restoration of the ringing key to normal position, relays 55 and 56 release. The frequency of the current generated by the oscillator SO is thereby shifted back to normal so that in response thereto relay 57 releases and relay 35 operates. Relays 58 and 61 release on the release of relay 57 but relay 59 and those relays dependent thereon, remain operated because a ground for its locking circuit is established at the contact of relay 35 before being removed at the contact of slow release relay 36. 80

Further extension of the connection may now be made in the manner previously described after which conversation may ensue. At the conclusion of conversation, the plug is withdrawn and the apparatus restored to normal condition as in the manner previously described. 85

Should the operator at station W insert the plug into jack C, the low frequency line CL will be selected, for, upon the insertion of the plug, relay 64 operates causing the operation of relay 65, which, in turn, operates relay 34 and starts the oscillator SO. Relays 35 and 37 then operate and relay 36 releases. In response to the actuation of the ringing key of the connected cord circuit, relay 66 operates, causing the operation of relay 67 which connects condenser 40^c in the frequency determining circuit of the oscillator. The frequency of the oscillator is thus shifted. Current of the shifted frequency is selected by tuned circuit CTC and rectified by rectifier R and the resultant rectified current operates relay 68, whereupon relays 62 and 69 operate. The operation of relay 62 selects low frequency line CL and operates relay 61. Relay 69, in operating, locks up in the manner described in connection with relay 59 and operates relays CN and 70, as well as relays 42, 58 and 63. Relay CN connects balancing network NC in circuit with the line windings of the transformer 44 to balance the selected low frequency line CL. Relay 70 connects ringing current to the selected low frequency line. Relays 42, 58 and 63 connect a source of busy tone to the non-selected low frequency lines. Upon the restoration of the ringing key to normal position, relays 62, 61 and 68 release, relay 35 operates and relay 36 releases. 110 115 120

Low frequency line DL may be selected by inserting the plug of the cord circuit into jack D. The insertion of the plug into the jack causes the operation of relay 71 which, in turn, operates relay 72. Relay 72 operates relay 34 to start the oscillator. Relays 35, 36 and 37 function as before described. The actuation of the ringing key of the connected cord circuit causes the re- 125 130

spose of relay 72' which operates relay 73. Relay 73 operates to connect condenser 40^a in the frequency determining circuit of the oscillator thereby shifting the frequency 5 of the current generated thereby. The shifted frequency current is selected by tuned circuit DTC, and rectified by rectifier DR. The resultant rectified current operates relay 74. Relays 63 and 75 thereupon operate. Relay 63 selects the low frequency line DL and operates relay 61. Relay 75, in operating, causes the operation of relays DN, 76, 42, 58 and 62. Relay DN connects balancing network ND in circuit with the 10 line windings of transformer 44 to balance the low frequency line DL. Relay 76 connects ringing current to the selected low frequency line. Relays 42, 58 and 62 connect the busy tone source to the non-selected low 15 frequency lines. Upon restoration of the ringing key to normal position, relays 72, 73, 74, 63 and 61 release, relay 35 operates and relay 36 releases.

Should a call originate at the distant end 20 of low frequency line BL, CL or DL, the apparatus associated with the line on which the call originates operates as described in connection with line AL to operate the signal receiving apparatus associated with the 25 receiving jack E.

While only one channel of the multiplex carrier telephone system has been shown as equipped with apparatus for selecting any one of a plurality of low frequency lines, 30 signaling thereover and connecting the same to the channel of the multiplex system, other channels may be similarly equipped, if desired.

Likewise, in the system of Figs. 1 and 2 35 other channels of the multiplex carrier telephone system shown therein may be equipped with selecting mechanism similar to that illustrated in connection with one of the channels. The channels of the multiplex 40 system (Figs. 1 and 2) not equipped with selecting mechanism may be equipped with signaling mechanism such as disclosed in detail in connection with the west terminal of channel LFL₂ in Fig. 3.

The invention set forth herein is, of course, 45 susceptible of various other embodiments and applications.

I claim:

1. In a carrier wave signaling system, a 50 carrier wave channel, stations in which said channel terminates, a modulator at one station, a detector at another station, a plurality of low-frequency terminal circuits adapted to be operatively associated with 55 said modulator, a corresponding plurality of low-frequency terminal circuits adapted to be operatively associated with said detector, and means controlled in response to the taking for use of one of the first-mentioned terminal circuits for operatively 60 as-detector, and means controlled in response

sociating it with the modulator and for operatively associating one of the second-mentioned plurality of terminal circuits with the detector.

2. In a signaling system, a two-way carrier wave channel terminating in respective stations, a modulator and a detector associated with said channel at each station, a plurality of low-frequency terminal circuits at each station arranged for connection with the respective modulator and detector for repeating into and receiving from the carrier wave channel, and means controlled in response to the taking for use of one of the low-frequency terminal circuits at one station for operatively associating it with the modulator and detector of that station and for operatively associating one of the low-frequency terminal circuits at the other station with the modulator and detector of that station.

3. In a carrier wave transmission system, a carrier wave channel terminating at each end in carrier signaling apparatus, a plurality of low-frequency terminating circuits 90 adapted for interchangeable connection to the carrier signaling apparatus at each terminal of the channel, an operator's cord circuit including a key, means to connect the cord circuit to any of the terminal circuits 95 at one station, and means controlled in response to the connection of the cord circuit to a particular one of said terminal circuits and to the actuation of said key for connecting to the carrier signaling apparatus at the 100 distant end of the channel the corresponding terminal circuit thereof.

4. In a carrier telephone system, a carrier telephone channel, a detector therefor, a plurality of frequency selective circuits associated with the detector, a plurality of telephone lines, means controllable over said channel and including said detector for selectively operating certain of said selective 105 circuits to connect a desired telephone line 110 to said detector, and means for transmitting speech over said channel and the connected line.

5. In combination, a carrier wave channel including a modulator at one terminal and 115 a detector at the other terminal, a plurality of terminal circuits at each terminal adapted for connection respectively to the modulator and to the detector, and means including said channel and one of the terminal circuits connectible to the modulator for controlling connection of one of the terminal circuits to the detector, the particular terminal circuit connected to the detector being dependent upon the terminal circuit over 120 which the control is exercised.

6. In combination, a carrier wave channel, a detector therefor, a plurality of terminal circuits connectible interchangeably to said detector, and means controlled in response 130

- to the frequency of the wave transmitted over said channel for selecting and connecting one of the terminal circuits to the detector.
- 5 7. In a communicating system, a carrier wave channel terminating at one station in a detector, a group of lines adapted for connection interchangeably with said detector, means controllable over said channel for selecting a line and connecting it to the detector, and means to indicate all of the remaining lines of the group as inaccessible.
- 10 8. In a communicating system, a carrier wave channel, a group of lines adapted for operative association interchangeably with said channel, and means controllable over any line for operatively associating it with the channel and for indicating all of the remaining lines of the group as inaccessible.
- 15 9. In a communicating system, a carrier wave channel, means to transmit selectively over the channel waves having different frequency characteristics including a carrier wave controlled by the signals to be sent, a detector for said channel, a plurality of terminating lines adapted for selective connection to said detector, means controllable by waves transmitted over the channel and dependent upon the frequency characteristics of the wave for selecting and connecting one of the terminating lines to the detector, and means operating in response to the carrier wave for maintaining the selected line connected during the transmission of signals.
- 20 10. In a signaling system, a carrier wave channel terminating in a detector, a plurality of terminal circuits adapted for interchangeable connection to said detector, means controllable over said channel for selecting and connecting to the detector one of said terminal circuits, and means responsive to the selection of such circuit for applying signaling current thereto and indicating the remaining lines as inaccessible.
- 25 11. In a communicating system, a carrier wave channel terminating in a detector, a plurality of terminal lines adapted for interchangeable connection to said channel, a plurality of frequency-selective circuits op- eratively associated with the output of the detector, means for transmitting waves of different frequency characteristics over said channel, including the carrier wave, means including said frequency selective circuits 55 for severally connecting the terminal lines to the channel in response to a wave of given frequency characteristic transmitted thereover, and means for maintaining such connection under control of the carrier wave.
- 30 12. In a communicating system, a carrier wave channel, means to transmit a carrier wave and waves of other characteristics thereover, a plurality of terminal circuits 60 connectable to said channel, selective means, means actuated in response to receipt of the carrier wave for energizing the selective means, means to cause the selective means to select and connect to the channel a desired one of the terminal circuits, and means for thereafter maintaining the connection of the selected terminal circuit under control of the carrier wave.
- 35 13. In a carrier signaling system, a frequency-selective carrier transmission channel, means to transmit a wave of a particular frequency through said channel continuously during signaling periods, a plurality of terminal circuits, and means for transmitting waves of other frequencies within the transmission frequency range of said channel during non-signaling periods for operatively associating a selected one of said terminal circuits with said channel. 75
- 40 14. A multiplex carrier telephone system comprising a high frequency main line extending between two stations W and E, a plurality of low frequency lines radiating from station E, a plurality of balancing networks, one for each of the low frequency lines, and means at station E controlled over the main line from station W for selecting one of the low frequency lines and its balancing network and coupling the same to 90 one of the channels of the system.
- 45 In witness whereof, I hereunto subscribe my name this 12th day of September, A. D. 1923.
- 50 JACOB S. JAMMER.
